UNITED STATES PATENT OFFICE

JAROSLAV RAK, OF CHICAGO, ILLINOIS, ASSIGNOR TO VARIETY FIRE DOOR COMPANY,
A CORPORATION OF ILLINOIS

ELEVATOR DOOR

Application filed October 8, 1927. Serial No. 224,877.

This invention relates to elevator doors.

Although not limited to a particular door structure, the invention relates particularly to fireproof elevator doors or closures in which there are a pair of vertically sliding sections, which meet when the door is closed and separate vertically in opening.

I am aware that the lower sections of doors of this sort have been constructed and supported to form a truckable filler or bridge between the building floor and the floor of the elevator car when the door is open, but the stops or supports have usually either been attached to and carried by the vertical guides or they have had flanged support on the top of the building floor when the door is open.

In the first case the stresses imposed upon the guides is objectionable and in the second case, the motor is frequently burned out or other damage done by leaving a truck or other obstruction in such position on the building floor that it will obstruct the movement of the projecting, supporting and bridging plate or flange because of the projection of this flange over the floor of the building. In addition to this, the sections of the door have heretofore usually been free to separate from the wall with settling of the building, as well as under the stresses imposed by trucking across the door or any high or excessive temperatures to which the door may be subjected.

The object of the present invention is the provision of a generally improved and simplified structure that may be economically produced and easily installed and which will provide a truckable filler or bridge without objectionable stresses upon the guides, as well as without the possibility of being obstructed by a truck or the like on the floor of the building, regardless of its position.

Another object is to provide for retaining the door sections against being forced away from the building wall and toward the path of movement of the elevator car, when the door is open.

The invention is illustrated in the accompanying drawings, in which

Figure 1 is an elevational view of a door embodying the present invention, looking

from the shaft side and showing the door in closed position;

Figure 2 is a detailed section taken on the line 2—2 of Figure 1;

Figure 3 is a vertical section taken on the line 3—3 of Figure 1 and showing the door sections in closed position; and

Figure 4 is a view similar to Figure 3 showing the door sections in open position.

To illustrate the invention, I have shown one door or any to which the invention is applied, it being understood that the details of the door per se form no part of the present invention, except as set out in the appended claim.

The door shown comprises an upper panel or section 5 and a lower panel or section 6, which may be suitably counterbalanced and which are connected by the connecting elements designated generally at 7 and which are trained over pulleys 8 suitably mounted upon the guides 9 which are secured to the building wall 10 and extend vertically along opposite sides of the door opening or passageway 12 on the shaft or elevator side of the wall. The elevator shaft is designated generally at 14 and a vertically movable elevator car is shown fragmentarily at 15.

The latching arrangement for the door is shown as comprising a disc 18 pivoted on the lower section 6 and provided with a handle 19. The disc 18 has pivoted thereto arms 20 and 21, the outer ends of which are arranged to engage suitable stops 22 secured to the sides 9. A spring 24 normally maintains the arms 20 and 21 in their projected positions and when the panels or sections 5 and 6 are brought together into closed position, as shown in Figure 1, the outer ends of the arms 20 and 21 are snapped over the projections and latch the door in closed position. When it is desired to open the door, the handle 19 is turned to rotate the disc 18 which disengages the arms 20 and 21 from the stops 22 so that the panels may be separated.

It frequently happens that when the panels or sections 5 and 6 are closed they come together with a considerable impact and to avoid the noise and jar on the door sections, in such a case, I provide a cushioning strip 100

25 which may be suitably attached to the bottom of the upper door section 5. This cushioning strip 25 may be of leather or other suitable material which will cushion any impact between the upper and lower sections 5 of the door as they are brought together.

For the purpose of stopping the downward movement of the lower section 6 and supporting the upper surface 28 thereof substantially flush with the surface 29 of the building floor 30 and substantially flush with the floor of the elevator car 15 when the door is open, a bar or strip 32, which may be of suitable metal construction, is suitably secured at 33 to the wall 10 just below the floor 30 and extends across the wall in the direction of the width of the door opening 12. The bar 32 may be uninterrupted from one side of the door to the other or it may comprise suitable spaced short strips or bars suitably attached to the wall of the building.

Cooperable with the stop or bar means 32 is a similar stop member or bar means 35 secured to the adjacent side of the door section or panel 6 and extending along the upper margin thereof. The upper edge of the stop means 32 is inclined or tapered at 38 and the lower edge of the stop member 35 is correspondingly tapered or inclined at 39 to interlock with the stop means 32 when engaged therewith and hold the section 6 against separation or movement away from the wall 10 when the door is open. This holds the panel 6 properly in place and against sagging away from the wall when the door is open and trucks are being run across the top of the door in passing from the floor to the elevator or vice versa.

The stop 32 and co-operating stop member 35 thereby perform the dual function of a stop and support means for stopping and supporting the top or upper surface 28 of the door section 6 so that it will lie substantially flush with the floors of the building and elevator car to form a truckable filler or bridge between the car 15 and the building floor when the door is open and binder or interlock means for interlocking the section 6 against separation from the wall 10.

50 The door sections 5 and 6 may have co-operating means 40 and 42 for additionally sealing the joint between the upper and lower sections 5 and 6 against drafts, fire and the like, when the door is closed. When the door is open the lower section 6 is hung and supported by the wall or sill and any trucking or other stresses are removed from the guides.

The combined stop, support and interlock means is relatively simple and inexpensive and may be conveniently installed.

Another important aspect of the invention is that very little space is required between the wall 10 and the door to accommodate this stop and interlock means. This space is reduced to a minimum as indicated at 45,

yet the bars 32 and 35 have great strength against the stresses, such as are imposed by trucking over the top of the lower section 6, when the door is open.

I claim:—

The combination with an elevator shaft having a door opening in the wall thereof with a building floor adjacent said opening, of a door section movable adjacent the wall of the shaft from closed position with its upper edge a substantial distance above the building floor to open position with its upper edge in substantial register with the building floor, said door having a frame, and means for arresting the movement of the door and for holding the door against separation from the wall when the bottom of the door has moved down into position a substantial distance below the floor and the top of the door is in substantial register with the floor, said means comprising a flat bar attached to the wall and extending across substantially the entire width of the door and having an inclined upper edge and a cooperating flat bar carried by the door for movement therewith and having an inclined lower edge co-operable with the inclined upper edge of said first bar outside the door frame and wholly within the space between the door frame and the adjacent wall, said cooperating bar extending across substantially the entire width of the door with its inclined edge cooperating with the inclined edge of said first bar substantially completely across the door opening.

In witness whereof, I hereunto subscribe my name this 6th day of October, 1927.

JAROSLAV RAK.
